UNITED STATES PATENT OFFICE.

CHARLES STEWART, OF PITTSBURGH, PENNSYLVANIA.

RAIL-JOINT.

1,026,718.

Specification of Letters Patent.

Patented May 21, 1912.

Application filed December 18, 1911. Serial No. 666,418.

To all whom it may concern:

Be it known that I, CHARLES STEWART, a citizen of the United States of America, residing at Pittsburgh, in the county of Allegheny and State of Pennsylvania, have invented certain new and useful Improvements in Rail-Joints, of which the following is a specification, reference being had therein to the accompanying drawing.

10 This invention relates to rail joints and has for its object to provide means in a manner as hereinafter set forth for efficiently connecting the opposing ends of a pair of track rails, at the same time providing for the necessary expansion and contraction of the rails when occasion so requires.

Further objects of the invention are to provide a rail joint which is simple in its 20 construction and arrangement, strong, durable, efficient in its use, conveniently set up, and comparatively inexpensive to manufacture.

With the foregoing and other objects in view, the invention consists of the novel construction, combination and arrangement of parts as hereinafter more specifically described and illustrated in the accompanying drawing, wherein is shown an embodiment of the invention, but it is to be understood that changes, variations and modifications can be resorted to which come within the scope of the claims hereunto appended.

35 In describing the invention in detail, reference is had to the accompanying drawing in which:

Figure 1 is a side elevation of a rail joint in connection with this invention, Fig. 2 is a 40 sectional plan, Fig. 3 is a cross sectional view, Fig. 4 is a perspective view of one end of the combined bolt retainer and fish plate, and Fig. 5 is a perspective view of a portion of the retaining plate for the combined bolt 45 retainer and fish plate.

Referring to the drawing, 6 and 7 denote a pair of track rails, each of which includes a web 8 formed with bolt openings 9. The bases 10 of the track rails are mounted upon 50 the base plate 11 of a rail chair, the latter having formed integral therewith a fish plate 12 which overlaps one side of the bases 10 of the track rails and abuts against the webs 8. The fish plate 12 is formed with a 55 series of bolt openings 13 through which extend the headed bolts 14. The heads of the

bolts are indicated at 15 and abut against the outer face of the fish plate 12. The shanks of the bolts 13 extend through the openings 9 and are provided with a reduced portion 16 at a point removed from their free ends. The base 11 of the rail chair is of greater width than the bases 10 of the track rails, under such conditions, projecting from the longitudinal edges of the bases 10 as at 17. The projecting portion 17 of the plate 11 approximately centrally thereof is formed with a longitudinally extending slot 18' for a purpose to be presently referred to.

Positioned against that side of the webs 8 opposite that side against which abuts the fish plate 12, is a combined bolt retainer and fish plate 18, the latter being formed with a longitudinally extending slot 19 and an enlarged opening 20 in proximity to one end of the slot 19. Each end of the plate 18 is formed with an outwardly extending rectangular lug 21 for a purpose to be presently referred to. The plate 18 is positioned 70 so as to engage the underneath face of the heads of the track rails and the upper face of the bases of the rails. The plate 18 is slid in position from one end so as to successively permit the passage of the bolts 9 through the opening 20, the reduced portion 60 of the shanks of each of the bolts being positioned in the slot 19, the shoulders 22 formed by the reduced portions of the shanks abutting against the outer face of the plate 18, and under such conditions, it does not necessitate the employment of nuts for maintaining the bolts in position from transverse movement. To prevent the plate 18 from longitudinal movement with respect 75 to the track rails, an angle-shaped retaining plate 23 is provided having openings 24 for the outer ends of the shanks of the bolts 14. The retaining plate 23 is positioned between the lugs 21 and upon the outer ends 80 of the shanks of the bolts. The retaining plate 23 centrally thereof is provided with a rectangular depending arm 25 which extends through the slot 18' and is maintained in position by a key 26 which extends 85 through an opening 27 of the arm 25 and engages the lower face of the base plate 11 of the chair.

To disconnect the track sections, it is necessary first to remove the retaining plate 110 23 after which the plate 18 can be slid longitudinally until the bolts 9 are successively

removed through their respective bolt openings.

What I claim is:—

1. A rail joint comprising a combined rail chair and fish plate positioned in operative relation with respect to a pair of track rails, bolts extending through said fish plate and the track rails, said bolts having their shanks provided with reduced portions, a longitudinally slotted fish plate mounted upon the reduced portions of said shanks and engaged by the shoulders formed by the reduced portions to prevent transverse movement of said bolts, and means engaging with the rail chair and mounted upon said bolts to prevent longitudinal movement of said slotted fish plate.
2. A rail joint comprising a combined rail chair and fish plate positioned in operative relation with respect to a pair of track rails, bolts extending through said fish plate and the track rails, said bolts having their shanks provided with reduced portions, a longitudinally slotted fish plate mounted upon the reduced portions of said shanks and engaged by the shoulders formed by the reduced portions to prevent transverse movement of said bolts, said slotted fish plate

provided at each end with an outwardly extending lug, and means mounted upon the shanks of the bolts, interposed between said lugs and connected with said chair to prevent longitudinal movement of said slotted fish plate.

3. A rail joint comprising a pair of fish plates, one of said plates provided with a longitudinally extending slot, said plates positioned in operative relation with respect to a pair of track rails, bolts extending through said fish plates and the track rails, said bolts having their shanks provided with reduced portions positioned in the slotted fish plates, the shoulders formed by said reduced portions abutting against the slotted fish plates thereby preventing transverse movement of the bolts, and means mounted upon the shanks of the bolts to prevent longitudinal movement of said slotted fish plate.

In testimony whereof I affix my signature in the presence of two witnesses.

CHARLES STEWART.
